UNITED STATES PATENT OFFICE.

SHADRACH MILES DOBSON, OF PORTLAND, MAINE.

STEAM-TURBINE.

1,068,833.

Specification of Letters Patent.

Patented June 3, 1913.

Application filed April 22, 1912. Serial No. 692,830.

To all whom it may concern:

Be it known that I, SHADRACH MILES DOBSON, a citizen of the United States, residing at Portland, county of Cumberland, State of Maine, have invented certain new and useful Improvements in Steam-Turbines, of which the following is a specification.

This invention relates to turbines and particularly to a steam turbine.

The principle involved in my invention is dependent upon the tendency of the moving particles of fluid to communicate motion to adjacent particles. I have discovered that a stream of vapor, such as steam, within certain limits which I will hereinafter describe will exert a continuous propulsive tendency upon surrounding walls if they be capable of movement in the direction of the flow of the vapor. In applying this principle I have devised a continuous spiral turbine through which steam may be forced so that, without buckets or impact blades, I am able to secure a complete utilization of the force of the steam down to its exhaust at atmospheric pressure.

The construction and operation of my turbine will be more fully described in the specification which follows.

10 In the drawings which form a part of this specification I have shown a simple form of turbine which I have found to be highly efficient and especially adapted to such work as the drive of generators and similar uses.

Throughout specification and drawings like reference numerals are employed to indicate corresponding parts, and in the drawings:—

40 Figure 1 is a side view, partly in section, of a simple turbine in accordance with my invention mounted with a generator, Fig. 2 is a section on the line 2—2, Fig. 1, looking toward the left, and Fig. 3 a section on the line 3—3, Fig. 1, looking toward the right.

45 My turbine, as shown, comprises a cylindrical casing 1 between which and the core 3 is set a continuous spiral 2. The walls of the spiral 2 are set with not over one eighth of an inch spacing between their adjacent surfaces. This gives a spiral groove about the drum 3 of not over one eighth of an inch in width and continuous from the intake 4 to the exhaust end 5. At the exhaust end 5 is a chamber 6 and at the intake end 4 is a chamber 7.

The steam pipe 8 passes through the support 15 and supplies the steam to two oppositely disposed nozzle arms 9 having mouths 9¹ disposed to deliver steam into the intake or intakes 4. It will be understood that the spiral walls 2 may be formed by one or more spiral flanges, there being a corresponding number of nozzle arms 9 preferably provided for delivering the steam direct to the intakes 4, although the chamber 7 will be maintained at substantially the boiler pressure.

The nozzles 9¹ are employed to deliver the steam jets through the grooves between the spiral walls 2. This is for the reason that my turbine operates in the direction of the flow of the vapor stream instead of taking its rotary motion on the reaction principle usually employed in rotary motors. For this reason the spiral of my turbine approaches for its maximum efficiency the true rotational plane or the plane at right angles to the axis instead of approaching the steeper inclines which seek to approach the transverse position. My spiral walls 2, therefore, are set on a very slight incline or pitch, so that the vapor may flow as nearly in the plane of rotation of the engine as is possible while having it travel longitudinally of the axis of rotation.

50 I have indicated at 11 a shaft of a generator 12 which is coupled to my engine on the side of the exhaust port 13. This exhaust port 13 might be connected with any suitable exhaust pipe but in the simple form which I have shown I have not deemed it necessary to illustrate any conductor for the escaping steam.

55 At the opposite end of the turbine casing 1, I have provided a tubular bearing 16 which runs in rollers 17 set in a frame 18. Within this bearing 16 is a shell 19 having a carbon packing 21 within which may be set an asbestos packing 20. The shell 19 is held with a steam tight fit against the end of the casing 1 by a spring 22 set on a collar 23 held fast by set screws 24 on the intake 8.

60 Adjacent to the exhaust 5 of my turbine spiral I preferably locate a bucket 14 for the purpose of assisting in starting the rotary motion of the turbine. This bucket, however, is more auxiliary and the effectiveness of the spiral in the direction of the flow of the vapor is wholly independent from the reaction tendency of the bucket.

65 In starting the turbine the flow through

the spiral will at first produce only a very gradual overcoming of the inertia of the engine. During that period sufficient pressure will pass through the spiral to exert a strong influence on the bucket 14 by reaction. After the turbine has been speeded up, however, the action of the steam throughout the turbine will be continuous and the steam upon reaching the bucket 14 will be at substantially atmospheric pressure so that there will be comparatively little effect produced by the bucket in the general running of the motor except as the steam pressure varies.

Various modifications may obviously be made in the form and type of my motor as long as the continuous action of the vapor stream upon the confining walls in its passage through the motor is maintained. These various modifications are all within the spirit of my present invention if within the limits of the appended claims.

What I, therefore, claim and desire to secure by Letters Patent is:—

1. A rotary motor comprising a rotary shaft, a drum on said shaft and having a continuous passage in a plurality of turns spirally disposed thereabout in the direc-

tion of the rotation thereof, a casing inclosing said shaft, an axial vapor supply entering said drum at one end, a nozzle arm within said casing and a nozzle on said rim and directed toward said passage in substantial alinement therewith.

2. In a rotary motor, a casing, a tubular bearing on said casing and having an opening therethrough, an intake pipe passing through the opening of said bearing and entering said casing, a shell surrounding said intake pipe, a carbon pack in said shell and bearing against said casing around the entry of said intake pipe and a resilient packing for said shell.

3. In a rotary motor a rotatable steam drum, a tubular bearing at one end thereof, a concentric intake pipe entering said bearing, a frame inclosing said bearing and a plurality of rollers mounted on said frame and supporting said tubular bearing.

In testimony whereof I affix my signature in presence of two witnesses.

SHADRACH MILES DOBSON.
